CLAIM

The ornamental design for front bezel for a computer enclosure, as shown and described.

DESCRIPTION

FIG. 1 is a perspective view of front bezel for a computer enclosure showing my design;

FIG. 2 is a front elevational view thereof;

FIG. 3 is a left side, elevational view thereof;

FIG. 4 is a right side, elevational view thereof;

FIG. 5 is a top plan view thereof; and

FIG. 6 is a bottom plan view thereof; and,

FIG. 7 is a perspective view of the front bezel being mounted to a computer enclosure.

Broken lines shown in the drawings illustrate portions of computer enclosure and form no part of the claimed design.
